UNITED STATES PATENT OFFICE

2,509,861

SPRAY PARTICLE COLLECTOR

Lyle Melvin Cooper, Rahway, N. J., assignor to
 Standard Oil Development Company, a corporation of Delaware

Application July 24, 1947, Serial No. 763,207

7 Claims. (Cl. 73—432)

1

The present invention relates to a method and apparatus for evaluating the character of a spray of fluid or any other material, such as a finely divided solid material, projected from a spray nozzle or a jet.

It is an object of the invention to provide a method and means whereby the particle size and pattern of any given spray may be rapidly and visually determined. It is a further object of the invention to provide a method and means whereby a substantially instantaneously recorded impression may be obtained of the condition existing in any transverse plane through a spray issuing from a jet or spray nozzle.

In the production and use of sprays of fluids and other materials capable of being broken up into streams of finely divided particles by being forced through a restricted opening, it is extremely important that the particle size and distribution as well as other characteristics of the spray be readily determinable. These characteristics vary according to spray orifice size, spray pressure, type of material being sprayed, etc. To obtain optimum results, adjustments of the spray are made during operation, on the basis of the characteristics observed.

In the past, it has been customary to evaluate spray characteristics by visual inspection, or by methods such as gauging the time required to atomize a unit quantity of a given material, or the measurement of precipitation at a fixed distance from a spray nozzle, or within a specified time period. The effectiveness of such methods depends entirely upon the experience, judgment, and ability of individuals, and the results obtained vary accordingly. By means of the present invention, spray evaluation, and consequently adjustment for optimum effect may be reduced to a previously unobtainable exactness.

The nature and objects of the invention may be fully understood from the following description when read in conjunction with the accompanying drawings, in which:

Fig. 1 is a vertical section, from front to back, of a suitable apparatus.

Fig. 2 is a perspective view from the front end with parts broken away.

Fig. 3 is a perspective view of a portion of the interior, showing the slide holder.

Referring now to the drawings, the numeral 1 designates a carrier container or case for the mechanism of the device. This case is provided with a sized orifice 1a, in its forward end, and a hand hole 1b at the opposite end. A cover or door 1c normally closes the hand hole.

2

As shown, the operating mechanism comprises a pair of opposed pulleys or rollers 2a and 2b disposed on shafts laterally of the case at the upper and lower corners of the forward end of the case. A thin, flexible shutter belt 3, having a rectangular opening or slot 3a disposed in spaced relation to the ends of the belt, extends over the rollers 2a and 2b so as to normally close the orifice 1a. A thin felt or rubber gasket 4 may be interposed between the inner edges of the orifice 1a and belt 3 to provide a substantial seal between them, or a smooth metal rim for the orifice opening may be applied so as to frictionally engage the outer surface of the belt.

15 The upper end of belt 3 passes through a slotted stop member 5 secured laterally of the case at its upper end, and is securely gripped by clip member 6. The member 6 is provided with an operating lug 6a extending upwardly through and beyond the upper end of the case by way of a slot 1d therein. A rearwardly extended cocking piece 6b is also provided on clip 6. The cocking piece may be slotted as shown, or provided with a downwardly extended lip to engage a sear lug 7a on a trigger arm 7. The trigger arm is pivotally mounted in the case by means of a pin 8, transversely of the case, and the arm extends rearwardly through the case by way of a slotted opening 1e. A spring 9 normally maintains the arm 7 in a cocked position.

At the lower end of the belt 3 a clamp member 10 provides for engagement between the belt 3 and the operating spring 11, which in turn engages a tension adjusting bolt 12 extending through a fixed support 13. Tension of the spring is adjusted by means of a wing nut 14 on the bolt 12, which nut engages the support 13.

At a point immediately to the rear of the orifice 1a, and spaced therefrom just sufficiently 40 to permit passage of the belt 3 between a removable plate holder 15 is suspended transversely of the case 1 by means such as lugs 16. The plate holder 15 is provided with upper and lower grooved ways or channels 15a and 15b into which may be fitted a plate or slide member 17. The channel portions 15a and 15b are preferably of such thickness at their forward edges as to permit sliding contact with the belt 3, while preventing contact of the belt with the face of the plate 17. The numeral 18 designates a spray nozzle.

In operation, the operating lug 6a is drawn rearwardly until the cocking piece engages the sear 7a, placing the spring 11 under tension. By 55 means of the clamp 6, the belt is thus drawn

rearwardly into the upper part of the case, with the slot 3a raised to a point above the orifice 1a and slide 17. With the mechanism thus cocked, the case is inserted into the spray from nozzle 18 at right angles to the line of discharge, and to any point in the spray for which the required data is desired. The trigger 7 is then depressed to release the cocking piece 6b from the sear 1a, and the spring 11 then draws the belt downwardly past the orifice 1a and plate 17. As the belt 3 moves downwardly, the slotted portion 3a momentarily exposes the plate 17 to impingement of spray particles from the jet 18, which record thereon their characteristic size and pattern. With liquid sprays, a plate of plain glass or other material such as plastic, metal, wood or the like may be utilized, but with other fluids and with finely divided solids, it is preferable that the plate 17, formed of any similar material, be coated with an adhesive, or an impressionable material such as gelatin.

The invention has been set forth with reference to a specific form of apparatus and a method of operation, merely for the purpose of illustration, and is not to be considered as limited thereto, but only by the appended claims.

I claim:

1. A method of visual determination of the particle size and pattern of material discharging from a spray nozzle, comprising introducing into the spray of material a masked spray particle collecting element, and momentarily unmasking said element, exposing a surface thereof to impact of the spray, whereby said surface may receive and retain an exact imprint of the character and material content of the spray in the area of exposure.

2. Apparatus for visual determination of the particle size and pattern of material discharging from a spray nozzle, comprising a carrier container having an orifice in one wall thereof, a movable shutter interiorly of the container, normally covering the orifice, a removable holder element supported within said container rearwardly of the shutter, coincident with said orifice, a particle collecting slide member carried by

said holder element, and means for activating said shutter to expose the surface of said slide member momentarily to a spray entering through said orifice.

5. Apparatus according to claim 2 in which the movable shutter is of the focal plane type.

4. Apparatus according to claim 2, in which the slide member is a glass slide coated with an impressionable coating material.

10. 5. Apparatus for visual determination of the particle size and pattern of material discharging from a spray nozzle, comprising a case, spray particle collecting element removably supported within said case, an orifice opening into said

15. case toward said element, a shutter closure for said orifice normally masking said element, shutter actuating means associated with said case connected to and operable to actuate said shutter momentarily to open the orifice and unmask

20. said element, exposing the element to impact of material discharged from a spray nozzle through said orifice, and a surface coating on said element of an impressionable surface coating material adapted to receive and retain an impression of the spray of material discharged from the nozzle through said orifice.

25. 6. Apparatus according to claim 5 in which the surface coating on said spray particle collecting element is an impressionable gelatinous material.

30. 7. Apparatus according to claim 5, in which the surface coating on said spray particle collecting element is an impressionable adhesive material.

35.

LYLE M. COOPER.
